UNITED STATES PATENT OFFICE

127,803

DESIGN FOR A POURER FOR BOTTLES

Morris Holtz, Newark, N. J., assignor to Browne
Vintners Co. Inc., New York, N. Y., a corpora-
tion of Delaware

Application January 9, 1941, Serial No. 97,917

Term of patent 3½ years

To all whom it may concern:

Be it known that I, Morris Holtz, a citizen
of the United States, residing at 691 Elizabeth
Avenue, Newark, in the county of Essex, and
State of New Jersey, have invented a new, orig-
inal, and ornamental design for a Pourer for
Bottles, of which the following is a specification,
reference being had to the accompanying draw-
ing, forming part thereof.

In the drawing:

Fig. 1 is a side elevational view of a pourer for
bottles, showing my new design;

Fig. 2 is a front elevational view thereof;

Fig. 3 is a top view; and

Fig. 4 is a bottom view.

The opposite side of the device is substantially
similar to the side illustrated in Fig. 1 of the
drawing.

I claim:

The ornamental design for a pourer for bot-
tles, as shown and described.

MORRIS HOLTZ.
